UNITED STATES PATENT OFFICE.

ALLEN S. PATTISON AND HUBERT A. PATTISON, OF WASHINGTON, DISTRICT OF COLUMBIA, ASSIGNEES TO CENTRAL RAILWAY SIGNAL COMPANY, OF PITTSBURGH, PENNSYLVANIA, A CORPORATION OF NEW JERSEY.

METHOD AND APPARATUS FOR THE MANUFACTURE OF RAILWAY SIGNAL-TORPEDOES.

1,282,624.

Specification of Letters Patent. Patented Oct. 22, 1918.

Application filed December 10, 1915. Serial No. 66,174.

To all whom it may concern:

Be it known that we, ALLEN S. PATTISON and HUBERT A. PATTISON, citizens of the United States, residing at Washington, in the District of Columbia, have invented certain new and useful Improvements in Methods and Apparatus for the Manufacture of Railway Signal-Torpedoes, of which the following is a specification, reference being had 10 therein to the accompanying drawing.

This invention relates to improvements in a method and apparatus for the manufacture of railway signal-torpedoes.

The primary object of this invention is to 15 manufacture railway signal torpedoes by a continuous operation and from a strip or strips of paper, fabric or other flexible material.

A further object of this invention is to 20 manufacture railway signal torpedoes from a continuous strip of paper, fabric or other suitable flexible material in which is formed cavities to receive the explosive compound and to inclose this compound by a second 25 continuous strip, the method being continuous in its operation from the strips to the finished torpedo.

A further object of this invention is to 30 manufacture railway signal torpedoes by simultaneously feeding a continuous main or carrier strip of suitable material; forming therein explosive receiving recesses; filling the said recesses with an explosive and feeding a continuous bottom strip and cementing 35 it to the continuous carrier strip to form a bottom for and inclosing the said explosive, whereby a completed railway signal torpedo is made by a continuous operation.

A further object of this invention is to 40 manufacture railway signal torpedoes by simultaneously feeding a main or carrier strip of suitable flexible material; forming therein explosive receiving recesses; filling the recesses with explosive; feeding a continuous explosive inclosing containing strip 45 and cementing it to a carrier strip; feeding the rail-engaging straps on top of the explosive inclosing strip and feeding a continuous bottom strip over the rail-engaging

straps and cementing it to the said supplementary strip, whereby a completed railway signal torpedo is made by a continuous operation.

A further object of this invention is to provide an apparatus for the manufacture 55 of railway signal torpedoes whereby the explosive containing case is manufactured from a continuous strip or strips of paper or other suitable flexible material so arranged that the explosive is placed within the case in 60 the process of its manufacture, and whereby, if desired, a rail-engaging strap can also be attached to the torpedo by feeding a second continuous strip which will also form the bottom wall of the case, as well as unite the 65 strap thereto.

In the accompanying drawing—

Figure 1 is a side elevation, partly in section, of an apparatus which is illustrative of one manner of carrying out the method of, 70 and is the preferred generic form of apparatus which is also the subject-matter of the present invention.

Fig. 2 is a top plan view of the said apparatus.

Fig. 3 is a detached perspective view showing that part of the apparatus which accomplishes an intermittent feed and showing the dies or molds which form the carrier chain and in which the explosive carrying 80 strip is shaped.

Fig. 4 is an enlarged detached perspective view of the roller, which is a combined feeding and strip pressing roller.

Fig. 5 is a side elevation of the lower end 85 of the knife that serves to cut the strip into the separate torpedoes.

Fig. 6 is an enlarged sectional view of one form of explosive that may be used.

Fig. 7 is a detached perspective view showing one form of torpedo that may be made by this process and apparatus.

Fig. 8 is a perspective view of another form of torpedo that may be made by this method and apparatus.

Fig. 9 is a transverse sectional view of one form of torpedo manufactured by our machine.

Fig. 10 is a transverse sectional view of another form of torpedo produced by our machine.

Fig. 11 is a transverse sectional view of a 5 third form of torpedo capable of being produced by our machine.

In carrying out this invention, we preferably use an apparatus of the construction here shown and in which there is utilized 10 a table 1, having at its respective ends shafts 2 and 3. Each of these shafts has fixed thereon a six-sided elongated block 4. A chain of female dies or molds 5 passes around these elongated blocks and their bottoms to slide or travel over the table 1.

Each of these dies 5 is provided with a recess 6, and at its opposite edges is also provided with suitable pins or shoulders 7. As shown, these dies are preferably hinged 20 at or approximate their lower edges, as shown at 8, so that the chain of dies will pass around the six-sided elongated blocks 4, and the sides of the blocks 4 are equal in width to the length of the dies, and in that 25 way the blocks act like a sprocket wheel to cause the chain of dies to travel when either one of the shafts 2 or 3 is caused to rotate. Located at the receiving end of the table 1, is a roll of paper 9, which is of a width 30 equal to the width of the torpedo to be made. Supported by a suitable bracket 10 is a reciprocating male die 11, adapted to coöperate with the dies constituting the chain to form explosive receiving recesses 12, in the 35 strip of paper as it is being fed through the machine. Preferably, there is provided a moistening brush 13, of any suitable construction for slightly moistening the strip of paper so that the recesses can be more 40 readily formed therein by the said dies. A suitable spring depressed footpiece 14 is carried by the die 11 for the purpose of clamping the paper around the recess 6 in advance of the engagement of the paper by 45 the male die 11, thus preventing the paper from being drawn by the action of the dies except where the recess is formed.

The chain of dies of the construction here 50 shown is intermittently moved. When in the position shown in Fig. 1, the chain is quiet and at this moment the male die 11 is depressed, thus forming in the paper strip the explosive receiving recess 12. After 55 this recess is formed and the die 11 is withdrawn, then the chain is moved a distance just equal to the size of the dies and brings the next succeeding female die 5 in position under the male die 11. This intermittent movement is accomplished as follows:

60 At the receiving end of the table there is located a shaft 15, which carries a segmental roll 16 of suitable yielding material and this is located directly over the elongated six-sided block at the receiving end of the ma-

chine. The shaft 15 is continuously rotated 65 by means of a sprocket wheel 17, and a sprocket chain 18, the latter passing around a sprocket wheel 19 on a continuously driven driving shaft 20. The said shaft 2 which carried the elongated six-sided block 4, is 70 provided with a gear wheel 21 and the adjacent end of the shaft 15 is provided with a segmental gear 22. This segmental gear 22 has sufficient gear teeth to rotate the shaft 2 a distance equal to the length of the dies 75 5, so that at each revolution of the shaft 15, the shaft 2, with its elongated block 4, is rotated just far enough to carry the female molds 5 in succession under the male die 11, for the purpose already stated. When the 80 smooth or the gearless portion of the wheel 22 is over the gear 21, the chain of dies is quiet and at this moment the male die is forced downward thus forming the recess in the continuous strip 9. An eccentric 85 24 is carried by the shaft 20, and this eccentric forces the male die 11 downward when the chain of dies is quiet through the medium of an eccentric strap 25, which has its lower end connected with the upper end of the 90 male die stem 26.

While we have here shown the recess 6 round, for making a torpedo 27 of the form shown in Fig. 7, we desire it to be understood that the recess may be of other contours. For instance, it may be made of oval or elongated shape for the purpose of forming 95 a torpedo, such as 28 in Fig. 8.

After the explosive receiving recesses are 100 formed in the strip 9, the explosive is placed within these recesses. Preferably the explosive is of the well-known plastic type and will preferably be held on a suitable shelf or tray 29 from which the operator will 105 take the tablet and place it in the recess. After this is done and as the chain of dies and explosive containing strip is moved along, a second strip of paper, or other suitable material of the same width, is cemented 110 over the explosive, thus completing the torpedo case and forming a bottom therefor. When the torpedo is formed of only two walls, viz., the main or carrier wall, then it is necessary to attach the rail-engaging 115 strap or member 30 to the torpedo after it is completed in any well-known or desirable manner. When the torpedo is completed without the rail-engaging member or strap, a second roll of paper or suitable material 31 is supported on the bracket 10, and the 120 under side of this strip will engage the periphery of a roll 32 that is caused to dip into a suitable cement (not shown) located within a receptacle 33, and thus apply cement to the under side of the strip 31. This strip 31 passes under a spring pressed roll 34 of suitable yielding material and is 125 pressed down in contact with and cemented

to the carrier strip, thus completing the torpedo. This roll 34, as here shown, is driven by a sprocket chain 35 that passes around a sprocket 36 on the shaft of said roll and a sprocket wheel 37 which is carried on the end of the shaft 3. After the torpedo case is thus formed, the strip is severed between the explosive receiving recess by a suitable knife 38, and this knife is reciprocated by an eccentric 39 and an eccentric strap 40 in unison with the reciprocation of the male die, so that the knife moves down when the chain of dies and the strip of torpedoes are not moving, and the torpedoes are severed, as shown at 41 and will fall into any suitable receptacle 42.

Our invention, however, contemplates not only the completion of the torpedo without the rail-engaging strap, but also contemplates the simultaneous attaching of the rail-engaging strap so that when the torpedo falls from the machine, it is a completed article. This is accomplished by providing an additional strip 43 of paper or suitable material (shown in dotted lines) and this will be applied to the carrier strip 9 over the explosive and completes the case. In this instance, 43 will form the closing member of the case or bottom. After this strip is applied, then the rail-engaging straps 30 are applied on top of the strip 43 by placing them between the pins or shoulders 7 of the female dies, then afterward the strip 31 is cemented in position over the rail-engaging strap 30 and serves to unite the rail-engaging strap to the torpedo and further serves as an auxiliary bottom for the torpedo.

This strip 43 is provided with suitable cement at its under side in the same manner as described in respect to the strip 31 and as indicated in dotted lines at 44, and will also be pressed in position by a spring depressed roll like 34, which is diagrammatically shown in dotted lines at 45.

The primary object of having a wall between the explosive and the rail-engaging strap is to prevent the metal strap from coming into direct contact with the explosive, and our invention contemplates the accomplishment of this result without the use of two strips as just described, by cementing a paper disk 46 to the explosive tablet 47 before the tablet is placed in the explosive receiving recess of the carrier strip. In this event, the rail-engaging strap 30 is placed over the disk 46 and the strip 31 and then cemented thereto, serving as a bottom for the case and to hold the strip and explosive therein.

However, we prefer the use of three strips, because the use of the disk 46 means a separate operation in the cementing of it to the explosive, which separate operation

is done away with when the three strips are used as described herein.

We wish also to have it understood that instead of cementing the disk to the tablet, as shown in Fig. 6, the disk could be separate from the tablet and the tablet and disk placed in the recess and then the strap over them and then the strip 31 cemented in position. However, this would require more care in the placing of the disk in position and the disk would be liable to displacement in the succeeding operation of placing the strap thereon and cementing the strip 31.

While we have here shown a strip wide enough for one explosive receiving recess, we desire it to be understood that the chain of dies could be sufficiently wide to have two or more recesses formed therein to form two or more torpedoes in a line with each other and the strip of paper to be made sufficiently wide for that purpose, the torpedoes then being severed longitudinally as well as transversely by means that would be readily conceived by any one skilled in the art and without departing from the spirit and scope of our invention.

The apparatus here shown is intended as only one mechanical expression for carrying out the method herein involved.

We desire it to be also understood that the apparatus here shown is a single mechanical expression of the inventive idea of simultaneously forming from a continuous strip or strips of paper a torpedo case; placing therein the explosive and forming the bottom inclosing member of the case from also a continuous strip.

We desire it to be understood that variations may be made in our method and apparatus which will still be within the scope and spirit of the appended claims.

Having thus described our invention, what we claim and desire to secure by Letters Patent is:

1. The method of manufacturing railway signal torpedoes, consisting in providing and feeding a continuous carrier strip and forming therein explosive receiving recesses, placing the explosive within the recesses, placing a strap separating wall over the explosives, placing straps over the said wall and feeding and cementing a continuous bottom strip over the said straps, whereby a continuous manufacture of the torpedoes is accomplished.

2. The method of manufacturing railway signal torpedoes, consisting in providing and feeding a continuous strip of fibrous material, forming therein explosive receiving recesses, placing an explosive in the recesses, feeding and cementing thereover a continuous flexible strip, placing over the strip a rail-engaging strap and feeding and cementing a continuous strip for holding

the straps forming a bottom, whereby a continuous manufacture of railway signal 65
torpedoes is accomplished.

3. An apparatus for the manufacture of 5
5 railway signal torpedoes, comprising a plurality of female dies connected and moving together, a table over which they are moving, means for supporting and feeding a continuous strip of flexible material over and along 10
10 with the said dies, a male die coöperating with the female dies to form explosive receiving recesses, means for supporting, feeding and cementing a continuous strip to the first said strip to complete the case, and an 15
15 explosive support located between the male die and the means for applying the second strip to the first strip.

4. An apparatus for the manufacture of 20
20 railway signal torpedoes, comprising a mold supporting table, a plurality of movable female dies moving over the said table, means for supporting and feeding a flexible strip over and along with the said female dies, a male die coöperating with the female dies to 25
25 form recesses in the said strip, and means for feeding and cementing a second strip to the first said strip to complete the case, and explosive and rail strap supports located between the male die and the point where 30
30 the second continuous strip is applied to the first strip, whereby the second strip serves to hold the explosive and the rail-engaging straps to the torpedoes.

5. An apparatus for the manufacture of 35
35 railway signal torpedoes, comprising a mold supporting table, a plurality of female dies movable together over and supported by the table, means supporting and feeding a flexible strip over and along with the female dies, a male die coöperating with the female dies to form explosive receiving recesses in the said strip, means for applying 40
40 successively at separated points two continuous strips over the first said strip, an explosive support located between the male die and the first of the second strips, and a rail-engaging support located between the said second strips for the purpose described.

6. An apparatus for the manufacture of 50
50 railway signal torpedoes, comprising a mold supporting table, a plurality of female dies movable together over and supported by the table, means for supporting and feeding a strip of flexible material over and along with the female dies, a male die coöperating with the female dies to form explosive receiving recesses, and means for applying two strips at separated points over the first said strip, an explosive charging point between the 55
55 male die and the two last said strips, and a strip rail-engaging strap charging point located between the two points of applying the two last mentioned strips, the parts combined for the purpose described.

7. An apparatus for the manufacture of 65
65 railway signal torpedoes, comprising a mold supporting table, a plurality of female dies hinged together and forming a continuous chain, rollers at the ends of the table around which the said chain of dies passes, means 70
70 for intermittently moving the chain a distance equal to the width of the said dies, means for feeding a flexible strip over and along with the said dies, a male die coöperating successively with the female dies while 75
75 they are quiet to form explosive receiving recesses, and means for feeding and cementing a strip to the first said strip thereby completing the torpedo cases in a continuous strip.

8. An apparatus for the manufacture of 80
80 railway signal torpedoes, comprising a plurality of female dies hinged together in a continuous chain, means for intermittently moving the said chain a distance equal to 85
85 the width of the respective dies, means for supporting and intermittently feeding a flexible strip upon and along with the said dies, a reciprocating male die coöperating with the said female dies to form explosive 90
90 receiving recesses in the said strip, means for feeding a second or bottom strip and cementing it to the first said strip, and means for reciprocating the male die while the chain of dies is quiet, the parts combined 95
95 for the purpose described.

9. An apparatus for the manufacture of 100
100 railway signal torpedoes, comprising means feeding a strip of flexible material, recess forming means which form explosive receiving recesses in the flexible strip, means feeding and cementing a second flexible strip over the explosives in said recesses, and means feeding and cementing a third flexible strip on the second strip for holding a rail 105
105 engaging strap between the two last mentioned flexible strips.

10. The method of manufacturing railway signal torpedoes, consisting in providing and feeding a continuous container strip 110
110 in an approximately horizontal position and forming therein explosive receiving recesses, placing the explosive within the recesses, placing strap separating wall over the explosive, placing straps over said wall and 115
115 feeding and cementing a continuous bottom strip over said straps, whereby a continuous manufacture of the torpedoes is accomplished.

11. An apparatus for the manufacture of 120
120 railway signal torpedoes, comprising a plurality of female dies, approximately horizontally movable, means for supporting and feeding a flexible strip of material over and along with the dies, a male die coöperating 125
125 with the female dies to form explosive receiving recesses in the flexible strip, means for feeding and cementing a second strip to

the first strip at a point removed from the male die to allow the explosive compound to be placed in the recesses, and a third strip cemented to the second strip at a point considerably removed from the point of cementing of the first and second strips whereby the rail attaching strap can be placed between the second and third strips.

In testimony whereof we hereunto affix our signatures in the presence of two witnesses. 10
